CLOSING AND RETARDING DEVICE.

Application filed January 28, 1924. Serial No. 688,943.

This invention relates to closing and retarding devices for doors and other units. The accompanying drawings exhibit, as one illustrative embodiment thereof, a door closing and retarding mechanism of the class ordinarily termed door checks, wherein a spring furnishes the closing power which is hydraulically controlled and checked.

In the drawings of this embodiment Figure 1 is a vertical section taken through the center of the assembled check; Figure 2 is a plan view showing the adjustable connection between the lever arm and the check; Figure 3 is a plan view looking into the empty casing; Figures 4, 5, 6 and 7 are plan views showing the cylinder, wing piston and co-operating elements in various positions; Figures 8, 9, 10 and 11 are partial vertical sections taken on the lines respectively indicated in Figures 4, 5, 6 and 7; Figure 12 is a plan view of the cylinder cup; Figure 13 shows the spring driver in elevation; Figure 14 is a diagrammatic rectilinear development of the surface of the spring driver to show the position of its ribs and cam lugs; Figure 15 is a plan view showing the spring driver in position relative to adjacent elements; Figures 16 and 17 are elevations illustrating various phases of the operation of the spring driver and co-operating elements; Figure 18 is an enlarged detail view illustrative of the centering action of the cam lugs and co-operating elements.

Referring to Figure 1, the compact arrangement of the operating parts permits their housing within a relatively small and symmetrical shell 20 which is screw-threaded at its upper edge to retain the cover 21. For charging the check with fluid, an opening through the cover 21 is threaded for the removable plug 21^a. The interior surface of the cover is provided with spaced piers 103 which serve as abutments for operating parts beneath them without obstructing the flow of the fluid. Integral with and rising from the cover is a packing box 22 upon which is screwed the packing nut 23 which, through the annular gland 24, compresses a suitable packing 25 seated within the packing box.

Rotatably within the packing box and packing is the neck 33 of the depending cylindrical spring driver 34. Referring to Figures 2, 16 and 17, the upper extremity

of the spring driver neck 33 is provided with two upwardly extending lugs 32 adapted to interlock with corresponding lugs of a worm wheel 30, which underlies the lever arm 28, with which the worm wheel and the spring driver are adjustably connected by a worm 31 rotatably carried in ears 31^a on the underside of the arm 28. The worm is provided at its ends with screw heads by which it may be turned and, through its engagement with the worm wheel, may vary and adjust the angular position of the arm 28 with relation to the depending spring driver 34.

The spring driver neck 33 receives the upper end of the central spindle 27, which projects upward through the center of the worm wheel 30 and is interlocked with the split hub of the lever arm 28, which is provided with a tightening bolt 29.

Thus, in operation, the lever arm 28, the central spindle 27, and the spring driver 34 are operatively integral, although the position of the spring driver relative to that of the spindle and lever arm may be rotatively and angularly adjusted as circumstances require.

Within the packing 25 the spring driver neck 33 is provided with a series of parallel grooves into which the packing may be pressed to prevent leakage between the spring driver neck and the collar 22. Further to guard against leakage, at a point just below the packing 25 an annular channel 37 drained by oblique passages 38, is formed in the cover and around the spring 90 driver neck.

Between the under side of the cover 21 and the head end of the spring driver 34 a washer 39 spaces the spring driver from the cover and prevents the obstruction of the 95 draining passages 38.

To prevent leakage between the spring driver neck and the central spindle 27, the lower inner portion of the neck is counter-bored to receive a packing 35 closely fitting 100 therein and pressed into grooves 36 on the spindle 27.

In operation, the check is attached to the door in any usual manner as by screws through the plate 126 (Figure 3), and the lever arm 28 is connected by the usual link to the door frame. Thus, in Figure 1, the opening movement of a right-hand door

would result in the left-hand free end of the lever 28 moving toward the reader.

The power element of the present illustrative embodiment is the helical spring 90 surrounding the spring driver 34. When the check operates upon a right-hand door, the lower end of the spring 90 is held against rotation; while the upper end of the spring is secured to and turns with the spring driver 34. When the check operates upon a left-hand door the upper end of the spring 90 becomes fixed, while the lower end of the spring attaches to and operates with the spring driver 34. 15 Whichever be the direction of door action, therefore, the spring, automatically reversible in its operation, is wound by the opening movement of the door, and exerts its unwinding or expanding force to close the door.

The top and bottom of the spring 90 are respectively anchored to and carried by circular carriers 91 and 92, surrounding the spring driver 34, and best shown in Figures 15 to 17. A satisfactory means of anchoring the spring to the spring carriers is illustrated in Figure 15 where the upper end of the spring is shown bent to form a hook 93 adapted to engage the edge of an opening cut through the carrier. Preferably the line of contact between this hook 93 and the edge of the opening should be radial to the center of the spring helix, so as to avoid twisting or bending action as the spring winds and unwinds.

The lower end of the spring may be similarly attached to the lower spring carrier 92.

Referring to Figure 15, upon the exterior periphery of the upper spring carrier 91 are two cam lugs 94, 95 located diametrically opposite each other, but in different horizontal planes, as shown in Figure 1. Referring to Figures 1 and 3, fixed to and projecting within the casing 20, respectively in the horizontal planes of the cam lugs 94, 95 are the pins 96, 97.

Similarly, (see Figures 1, 3, 16 and 17) the exterior periphery of the lower spring carrier 92 is provided with oppositely disposed cam lugs, 98, 99 positioned respectively to meet inwardly projecting pins 100, 101 fixed in the lower part of the casing 20.

Referring to Figures 1 and 3, the interior bottom of the casing 20 is provided with raised piers 102, similar in form and function to the piers 103 of the casing cover 21 already referred to. When the lower spring carrier 92 is turned towards the right, (see Figures 16 and 17) the inclined surfaces of cam lugs 98, 99 encounter the pins 100, 101, and wedge the spring carrier downwardly to and upon the piers 102. In this manner the spring carrier is held firmly against further rotation towards the right.

The spring carrier 92 may, however, be freely rotated towards the left, as indicated in Figure 17.

While rotation towards the right causes the lower spring carrier to be depressed and locked against further rotation in that direction, the upper spring carrier 91 operates oppositely. Rotating the upper spring carrier 91 towards the right causes its cam lugs 94, 95 to retreat from the pins 96, 97; while rotation towards the left causes the inclined faces of cam lugs 94, 95 to contact with pins 96, 97 and wedge the carrier upwardly against the piers 103 of the casing cover, where it is held firmly and locked against further rotation towards the left.

The spring carriers 91, 92 surround and are actuated by the spring driver 34, the exterior of which is provided (see Figures 13 to 17) with eight cam lugs 110, 111 positioned to engage eight similar, but oppositely inclined, cam lugs 120, 121, formed upon the interior walls of the spring carriers 91, 92. All the cam lugs 110, 111 upon the spring driver 34 are located in different horizontal planes, permitting extensive range of rotation of the parts; and each cam lug is located in the same horizontal plane with a complementary cam lug upon one of the spring carriers 91, 92.

Contributing to operative balance and efficiency, three of the cam lugs 110 upon the upper portion of the spring driver 34 are located at points circumferentially equidistant, the fourth cam lug being located in vertical alignment with one of the other three. The complementary cam lugs 120 upon the spring carrier 91 are similarly positioned, so as simultaneously to engage the cam lugs 110. The four lower cam lugs 111 of the spring driver 34 are similarly positioned, and in like manner simultaneously engage the similarly positioned complementary cam lugs 121 upon the spring carrier 92.

Further to promote operative efficiency, (see Figure 18) the exterior surface of the spring driver 34 immediately adjacent the inclined faces of the cam lugs 110, 111 has portions that are somewhat raised to form acclivities, 122, up and along which the previously described cam lugs 120, 121 of the spring carriers 91, 92 slide to meet and lock with their complementary cam lugs 110, 111 of the spring driver. In this manner the mutual engagement of the cam lugs not only locks spring carrier to spring driver relatively, but also accurately centers the one within and relatively to the other.

The spring driver 34 is also provided with three equally spaced ribs 115, which serve to limit the downward movement of spring carrier 91 and the upward movement of spring carrier 92.

In operation, opening a right-hand door

causes the rotation of the spring driver 34 in the direction of the arrow in Figure 16. The upper cam lugs 110 of the spring driver 34 meet and ride upon the cam lugs 120 of the spring carrier 91, wedging the carrier downwardly until its lower edge strikes the horizontal ribs 115, thus locking the carrier to the spring driver 34 and at the same time drawing the carrier away from frictional contact with the casing cover 21. This rotation of the spring carrier 91 by the driver 34 winds the spring 90 by its upper end, exerting force in the same direction upon the lower end, and upon the lower spring carrier 92. Consequently, the cam lugs 98, 99 of the lower spring carrier 92 meet the inwardly projecting pins 100, 101 (Figures 1 and 3) on the casing 20, and force the carrier 92 downwardly against the bottom of the casing, so locking it against further movement towards the right. Meanwhile, the upper edge of the lower spring carrier 92 is depressed from contact with the horizontal ribs 115, so that there is no frictional contact between the stationary lower carrier 92 and the rotating spring driver 34, and no frictional contact between the upper carrier 91 and the casing cover or other stationary parts.

Upon release of the open door, the recoiling spring returns the upper spring carrier 91 to the left, carrying with it the driver 34 and the door thereto connected.

In the case of a left-hand door, opening the door rotates the spring driver 34 in the direction of the arrow in Figure 17, whereupon the lower cam lugs 111 of the driver 34 meet the cam lugs 121 of the carrier 92, wedging the lower spring carrier 92 upwardly until its upper edge strikes the horizontal ribs 115, thus locking the carrier to the spring driver 34, and at the same time raising the carrier away from frictional contact with the bottom of the casing. This rotation of the spring carrier 92 by the driver 34 winds the spring 90 by its lower end, exerting a force in the same direction upon the upper end, and upon the upper spring carrier 91. Consequently, the cam lugs 94, 95 of the upper spring carrier encounter the pins 96, 97 fixed in the casing 20, and force the spring carrier 91 against the casing cover, locking it against further movement towards the left. Meanwhile, the lower edge of the spring carrier 91 is withdrawn from contact with the horizontal ribs 115, so that there is no frictional contact between the now stationary upper carrier 91 and the rotating spring driver 34, and no frictional contact between the now rotating lower carrier 92 and the casing bottom or other stationary parts.

Upon release of the open door the recoiling spring returns the carrier 92 to the right,

rotating with it the driver 34 to original 65 position.

Referring to Figure 1, positioned concentrically within the spring driver 34 is the cylinder 40 which contains the checking mechanisms. The upper edge of the cylinder 40 is internally threaded to receive the closing-plug 52 which is centrally bored to surround and form a bearing for the spindle 27, and is provided with packing 53 and a threaded packing gland 54 to prevent leakage. The exterior lower portion of the cylinder 40 is reduced in size to fit closely 70 within the cup 41, best shown in Figures 1, and 4-12.

This cup 41 (Figures 1 and 12) is perforated through its bottom at 43 and 44 to receive positioning dowels 45 and 46 (Figure 3) fixed in the bottom of the casing 20, and may be still further secured to the casing by screws passed through the openings 85 47 and 48 into corresponding threaded openings 49 and 50 tapped in the bottom of the casing. The wall of the cup 41 is vertically cleft at 51, (Figures 1 and 12) which permits it to clasp the cylinder 40 with a firm resilient grip, but allows the cylinder 90 to be turned in the cup for purposes hereinafter stated.

The bottom of the cup 41 is also perforated at 55 (Figure 12) to admit the pin 95 56 (Figures 1 and 3) which is fixed in the bottom of the casing and projects upward through the cup bottom into the curved slot 57 cut in the exterior bottom of the cylinder 40, as shown in dotted lines in Figures 4 to 100 7.

Thus the range of rotation of the cylinder 40 within the cup 41 is limited by the fixed pin 56 in the slot 57.

The interior bottom of the casing 20 (Figures 1 and 3) is provided with channels 58 to provide free passage for fluid to, under and around the cup 41. In the bottom of the cup, directly over one of these channels, is a port 59 for admission of fluid to the cylinder 40.

The bottom of the cylinder (Figures 4 to 11) is perforated by two ball check ports 60 and 61, adapted to permit free upward flow of fluid therethrough into the cylinder, and to prevent flow in the opposite direction. Since the ends of the slot 57 are respectively diametrically opposite these ball check ports 60, 61, (see Figures 4 to 7) and since the opening 59 (see Figure 12) in the cup 41 is diametrically opposite the pin 56 projecting through the opening 55, it is evident that when the cylinder 40 is turned in the cup 41 to its limit of movement in one direction (as shown in Figures 4, 5, 8 and 9) one of the ball check ports, 60, will register with the opening 59; while if the cylinder 40 be turned to its opposite limit (as

shown in Figures 6, 7, 10 and 11), the other ball check port, 61, will register with said opening 59.

Through the vertical wall of the cylinder 40, respectively in radial alignment with the ball check ports 60 and 61, are ports 62 and 63. Similar ports are provided through the vertical wall of the cup 41 at 64 and 65. When the cylinder 40 occupies the position shown in Figures 4, 5, 8 and 9, the ports 63 and 64 register and form a free passage for fluid in both directions; when in the position shown in Figures 6, 7, 10 and 11 the ports 62 and 65 so register.

Within and fixed to the wall of the cylinder 40, midway between the ball check ports 60 and 61, is the radial abutment 66. In the inner face of this abutment 66, throughout its vertical length, a channel is bored wherein is journaled an oscillatory damper 67 to prevent passage of fluid between the abutment and the central spindle 27 from one side of the radial abutment to the other. Any pressure tending to force fluid between the abutment and the spindle turns the damper 67 into contact with the spindle 27, ensuring a self-tightening closure automatically effective under all pressures and functioning with a minimum of friction and wear. Further, the considerable oscillatory range of the damper's action permits generous tolerance of dimension in the manufacture and fitting of the abutment 66 and spindle 27.

The lower end of the spindle 27 is reduced in diameter to pass through and be journaled in axial openings in the bottom of the cylinder 40 and the cup 41. Integral with the spindle 27 (see Figures 4 to 7) is the wing piston 68, the outer vertical edge face of which is channeled (similarly to the inner face of the abutment 66) to receive an oscillatory damper 69, effective in the same manner as the damper 67 to prevent the passage of fluid between the wing piston and the wall of the cylinder 40 from one side of the wing piston to the other. As in the case of the damper 67, the oscillatory range of the damper 69 produces tight closure at all pressures, with minimum friction, and permits liberal dimension tolerance in the manufacture and fitting of the cylinder 40 and the wing piston 68.

The lower portion of the spindle 27 (see Figures 1 and 8 to 11) is axially bored to form a fluid passage 75 into which projects a needle valve 70 of usual type. The needle valve stem is screw-threaded through the bottom of the casing 20 and is provided with a knurled button 71 for manual adjustment. Surrounding the valve stem is packing 72, a packing gland 73, and tightening nut 74 to prevent leakage.

Communicating with the passage 75 are

the radial passages 76 and 77, thereby establishing a by-pass from one side of the wing piston 68 to the other, through the spindle 27, this by-pass being susceptible of adjustable restriction by the needle valve 70.

Cut in and partially around the exterior of the spindle 27 is the groove 78 which forms a passage between the spindle and the abutment damper 67 when the spindle is in certain positions; and in the interior bottom of the cylinder 40, near the abutment 66, are cut the channels 79, 80 which provide free fluid passage under and past the wing piston 68 when the piston is near the abutment.

Figures 1, 4, 5, 8 and 9 show the parts in position for operation on a right-hand door. In Figures 4 and 5, the opening movement of a right-hand door would result in the counter-clockwise movement of the wing piston 68. Assuming the casing 20 partially filled with fluid which has flowed into and filled the spaces below and around the cup 41, fluid will also have flowed into the cylinder 40 through the port formed by the registry of ports 63 and 64 through the walls of the cylinder 40 and the cup 41. Upon opening the door (the parts being as shown in Figures 4, 5, 8 and 9) the spindle 27 and its wing piston 68 rotate counter-clockwise and force fluid already in the cylinder freely out through the ports 63, 64. Meanwhile, consequent upon this movement of the wing piston, more fluid is drawn freely into the cylinder through the ball check port 60.

Assume that the opening movement of the door ceases when the wing piston reaches the point indicated in Figure 5, and that the door is there released to begin its closing movement. The initial portion of the closing movement will be rapid for, although the ball check port 60 has closed, the groove 78 cut in the spindle 27 offers a passage between the spindle and the abutment damper 67. Continued rotation diminishes and finally closes this passage however, and the only egress for the fluid compressed between the piston 68 and the abutment 66 is through the passages 77, 75, 76, which are adjustably restricted by the needle valve 70. Thus the speed of the latter portion of the closing movement may be governed as desired.

When the door has nearly closed, however, and the wing piston 68 has almost returned to its position as shown in Figure 4, free egress for the fluid between the piston and the abutment 66 is again provided by the groove 79 (Figures 4 and 5) beneath the piston, so that the final closing movement of the door is rapid and unresisted.

To reverse the check for operation upon a left-hand door, it is only necessary to turn the cylinder 40 in the cup 41 until the parts are in the position shown in Figures 6, 7, 10

- and 11. This may be readily accomplished without opening or in any manner disassembling the check, merely by turning the lever arm 28 (and so the spindle 27 with its wing piston 68) in a counter-clockwise direction until the wing piston strikes the abutment 66—and then forcing continued rotation in the same direction, rotating the cylinder 40 by and with the piston 68, until the end of the slot 57 in the bottom of the cylinder strikes the pin 56, when further movement will be arrested, and the parts will be in the position shown in Figures 6, 7, 10 and 11.
- Obviously the cylinder may be returned to the right-hand door position by reversing the above operation.
- When the parts are in position to operate a left-hand door, as shown in Figures 6, 7, 10 and 11, the ball check port 61 is in communication with the fluid supply, since turning the cylinder 40 has now brought this ball check port into registry with the opening 59 through the bottom of the cup 41. Similarly, on the opposite side of the abutment 66, a free fluid passage is now formed by the registry of openings 62 and 65, while openings 63 and 64, previously in registry, have now been separated and so closed.
- Referring to Figure 6, opening the door causes the wing piston 68 to turn clockwise to the position, for example, shown in Figure 7, fluid being drawn freely into the cylinder through the ball check port 61, while the fluid on the other side of the piston 68 passes freely out of the cylinder through the ports 62, 65. Upon the closing movement of the door, the ball check port 61 closes; fluid passes freely through the groove 78 between the abutment damper 67 and the spindle 27, until the latter's continued counter-clockwise rotation turns the groove past the damper. The speed of the subsequent portion of the closing movement is then determined by the adjustably restricted flow of fluid through passages 76, 75, 77 until the piston 68 is close to the abutment 66 and bridges the channel 80, wherethrough free passage of fluid permits rapid final closing.

While one particular illustrative embodiment has been herein disclosed, the invention is not limited thereto.

Claims:

1. A hydraulic door check and closer comprising in combination a casing, a helical door-closing spring; cylindrical spring carriers covering and connected to the ends of the spring and provided with exterior and interior cam lugs; lugs set in the casing to engage the exterior lugs of the spring carriers whereby one of the spring carriers, upon being rotated from a given point in one direction, is moved out of frictional contact with other parts and secured against further such rotation relative to the casing, and whereby the other spring carrier, upon being rotated from a given point in the opposite direction one of the spring carriers is picked up, removed from frictional contact with other parts, and rotated by and with the spring driver, and whereby upon rotation of the spring driver from a given point in one direction one of the spring carriers is picked up, removed from frictional contact with other parts, and rotated by and with the spring driver, and whereby upon rotation of the spring driver from a given point in the opposite direction the other spring carrier is so picked up, removed from contact and rotated; hydraulic checking means positioned within the spring driver and comprising a cylinder, a wing piston mounted to oscillate therein and adapted to move freely in one direction but against hydraulic resistance in the opposite direction; and means for operatively interconnecting the spring driver, the checking means, and the door.
2. A hydraulic door check and closer comprising in combination a casing, a door-closing spring, spring carriers connected to the ends of the spring and provided with exterior and interior cam lugs, lugs set in the casing to engage the exterior lugs of the spring carriers whereby one of the spring carriers, upon being rotated from a given point in one direction, is removed from frictional contact with other parts and secured against further such rotation relative to the casing, and whereby the other spring carrier, upon being rotated from a given point in the opposite direction, is similarly removed from contact and secured against further rotation; a spring driver positioned within the spring and provided with cam lugs to engage the interior cam lugs of the spring carriers whereby upon rotation of the spring driver from a given point in one direction one of the spring carriers is picked up, removed from frictional contact with other parts, and rotated by and with the spring driver, and whereby upon rotation of the spring driver from a given point in the opposite direction the other spring carrier is so picked up, removed from contact and rotated; hydraulic checking means; and means for operatively interconnecting the spring driver, the checking means, and the door.
3. A hydraulic door check and closer comprising in combination a casing, a door-closing spring, spring-carrying means connected to the ends of the spring, spring-driving means, means for connecting the spring-carrying means to the spring-driving means, means for connecting the spring-carrying means to the casing alternately operable with

relation to the connecting means last named whereby upon rotation of the spring-driving means from a given point in one direction one end of the spring is held against rotation while the other end is wound, and upon rotation from a given point in the opposite direction the spring is oppositely held and wound, means whereby upon operation moving parts are withdrawn from frictional contact with adjacent parts; hydraulic checking means; and means for operatively inter-connecting the spring-driving means, the checking means, and the door.

4. A door check and closer comprising in combination a casing, a door-closing spring, spring carriers connected to the ends of the spring and provided with exterior and interior cam lugs, lugs set in the casing to engage the exterior lugs of the spring carriers whereby one of the spring carriers, upon being rotated from a given point in one direction, is removed from frictional contact with other parts and secured against further such rotation relative to the casing, and whereby the other spring carrier, upon being rotated from a given point in the opposite direction, is similarly removed from contact and secured against further rotation; a spring driver positioned within the spring and provided with cam lugs to engage the interior cam lugs of the spring carriers whereby upon rotation of the spring driver from a given point in one direction one of the spring carriers is picked up, removed from frictional contact with other parts, and rotated by and with the spring driver, and whereby upon rotation of the spring driver from a certain point in the opposite direction the other spring carrier is so picked up, removed from contact and rotated; checking means; and means for operatively inter-connecting the spring driver, the checking means, and the door.

5. A door check and closer comprising in combination a casing, a door-closing spring, spring-carrying means connected to the ends of the spring, spring driving means, means for connecting the spring-carrying means to the spring-driving means, means for connecting the spring-carrying means to the casing alternately operable with relation to the connecting means last named whereby upon rotation of the spring-driving means from a given point in one direction one end of the spring is held against rotation while the other end is wound, and upon rotation from a given point in the opposite direction the spring is oppositely held and wound, means whereby upon operation certain moving parts are withdrawn from frictional contact with adjacent parts; checking means; and means for operatively inter-connecting the spring-driving means, the checking means, and the door.

6. A door check and closer comprising in

combination a casing, a door-closing spring, spring-actuating means, means for selectively connecting the ends of the spring to the actuating means in accordance with the direction of movement from a given point, means for selectively securing the ends of the spring to the casing in accordance with the direction of movement from a given point, means operative upon movement in either direction to create a space between parts that would otherwise move and bear frictionally in contact with each other, checking means, and means for operatively inter-connecting the spring-actuating means, checking means, and the door.

7. A door check and closer comprising in combination a casing, a door-closing spring, spring-actuating means, means for selectively connecting the spring to the actuating means effective in accordance with the direction of movement from a given point, means for selectively securing the spring to the casing effective in accordance with the direction of movement from a given point, means operative upon movement in either direction to prevent friction between certain adjacent parts, checking means, and means for operatively inter-connecting the spring-actuating means, checking means, and the door.

8. A closing and checking device comprising in combination a power element, means for selectively rendering said power element effective in opposite directions, friction relieving means operative upon movement in either direction for relieving friction between certain parts, checking means, and means for operatively inter-connecting all said means.

9. A hydraulic door check and closer comprising in combination a casing, a helical door-closing spring, a cylindrical spring carrier covering and connected to one end of the spring and provided with exterior cam lugs, lugs set in the casing to engage said exterior cam lugs whereby said spring carrier, upon being rotated from a given point is moved out of frictional contact with other parts and secured against further rotation relative to the casing, a similar spring carrier covering and connected to the other end of the spring and provided with interior cam lugs, a cylindrical spring driver positioned within the last named spring carrier and provided with cam lugs to engage said interior cam lugs whereby upon rotation of said spring driver from a given point said last named spring carrier is picked up, removed from frictional contact with other parts, and rotated by and with the spring driver; hydraulic checking means positioned within the spring driver comprising a cylinder, a wing piston mounted to oscillate therein and adapted to move freely in one direction but against hydraulic resistance in

the opposite direction; and means for operatively inter-connecting the spring driver, checking means, and door.

10. A hydraulic door check and closer comprising in combination a casing, a door-closing spring, a spring carrier connected to one end of the spring and provided with exterior cam lugs, lugs set in the casing to engage said exterior cam lugs whereby said spring carrier, upon being rotated from a given point is moved out of frictional contact with other parts and secured against further rotation relative to the casing, a similar spring carrier connected to the other end of the spring and provided with interior cam lugs, a spring driver positioned within the spring and provided with cam lugs to engage said interior cam lugs whereby upon motion of said spring driver from a given point said last named spring carrier is picked up, removed from frictional contact with other parts, and moved by and with the spring driver; hydraulic checking means, and means for operatively interconnecting the spring driver, the checking means, and the door.

11. A hydraulic door check and closer comprising in combination a casing, a door-closing spring, spring-carrying means connected to one end of the spring, spring-driving means, means for connecting the spring-carrying means to the spring-driving means, means for securing the other end of the spring to the casing whereby motion of the spring-driving means may wind one end of the spring while the other end is held against rotation, means whereby upon operation of the parts, moving parts are withdrawn from frictional contact with adjacent parts, hydraulic checking means, and means for operatively inter-connecting the spring-driving means, checking means, and the door.

12. A door check and closer comprising in combination a casing, a door-closing spring, spring-carrying means connected to one end of the spring, spring-driving means, means for connecting the spring-carrying means to the spring-driving means, means for securing the other end of the spring to the casing whereby motion of the spring-driving means may wind one end of the spring while the other end is held stationary, means whereby upon operation of the parts, a moving surface that would otherwise have continued in frictional contact with an adjacent surface is withdrawn therefrom; checking means, and means for operatively inter-connecting the spring-driving means, checking means, and the door.

13. A door check and closer comprising in combination a casing, a door-closing spring, spring-carrying means to wind one end of the spring, spring driving means, means for connecting the spring-carrying means to the spring-driving means, means

for securing the other end of the spring to the casing, means whereby upon operation the spring-carrying means is prevented from frictional contact with an adjacent surface; checking means, and means for operatively inter-connecting the spring-driving means and the checking means.

14. A door check and closer comprising in combination a casing, a door-closing spring, spring-driving means, means for connecting the spring to the spring-driving means, means for securing the spring to the casing, and means whereby upon operation frictional contact between the spring-driving means and an adjacent surface is prevented; checking means, and means for inter-connecting the spring-driving means and the checking means.

15. A door check and closer comprising in combination a casing, a door-closing spring, spring actuating means, means for connecting a part of the spring to the actuating means, means for securing another part of the spring against movement, means operative to remove parts from frictional contact with each other, checking means, and means for operatively inter-connecting the checking means and spring.

16. A closing and checking device comprising in combination a power element, an operatively connected checking element, and means effective during operation of the device to separate surfaces from frictional contact with each other.

17. A door check and closer comprising in combination a casing, a door-closing spring, spring actuating means, means for connecting a part of the spring to the actuating means, means for securing another part of the spring against movement, checking means co-operating therewith and comprising a cylinder wherein a wing piston is mounted to oscillate against fluid pressure, said checking means, spring and connecting means lying one within another so as to be positioned substantially within the longitudinal dimension of the spring and means for relieving friction between certain parts during operation.

18. A door check and closer comprising in combination a casing, a door-closing spring, checking means co-operative therewith and comprising a cylinder and a wing piston therein mounted to move against fluid pressure, said checking means being operatively connected to and disposed within the longitudinal dimension of the spring.

19. A door check and closer comprising in combination door-closing means and checking means co-operating therewith comprising a cylinder provided with an interior abutment integral therewith, a wing piston adapted to oscillate within the cylinder, and fluid damper means moveably mounted upon the piston and operative in both directions

by fluid pressure to close the clearance between the cylinder and piston to prevent passage of fluid therethrough.

20. A door check and closer comprising

5 in combination door-closing means and checking means co-operating therewith comprising a cylinder, a piston therein movable against fluid pressure, and pressure responsive leakage prevention means actuated by 10 pressure in either direction to prevent such leakage between said piston and cylinder.

21. A door check and closer comprising in combination door-closing means and checking means co-operating therewith comprising

15 a cylinder, a wing piston therein mounted upon an oscillatory spindle, an interior abutment integral with the cylinder, and fluid damper means movably mounted upon the abutment and operative in both 20 directions by fluid pressure to close the clearance between the abutment and the spindle.

22. A door check and closer comprising in combination door-closing means and checking means co-operating therewith comprising a cylinder, a piston therein mounted upon

25 a spindle, an abutment within the cylinder, and fluid leakage prevention means actuated by pressure in either direction to prevent such leakage between the abutment and the spindle.

23. A door checking and closing device comprising in combination a casing, door-closing means, and checking means co-operating therewith comprising a perforated

35 cup secured to the casing, a cylinder frictionally gripped in and by the cup and provided with perforations so located as to register with perforations of the cup whereby by ingress and egress of fluid is permitted,

40 an abutment integral with the cylinder, a piston within the cylinder governed by fluid resistance to check the action of the door-closing means, and means for moving the piston against the abutment forcibly to move

45 the abutment and cylinder relative to the cup thus changing the registry of the perforations to set the device for reverse operation.

24. A door-closing and checking device comprising in combination a casing, door-closing means, and checking means co-operative therewith comprising a cylinder, means for securing the cylinder to the casing, ports in the cylinder, corresponding

55 ports and port closures outside and contiguous with the cylinder, a piston mounted for oscillatory movement in the cylinder, and means operable by movement of the piston so to move the cylinder relative to said outside ports and closures as to set the device for reverse operation.

25. A door-closing and checking device comprising in combination a casing, door-closing means, and checking means co-operative therewith comprising a hydraulic

cylinder and piston therein constructed and arranged to permit relative movement of the cylinder and casing to set the device for reverse operation.

26. A door closing and checking device 70 comprising in combination a casing, door-closing means, checking means co-operative therewith, and means operable without opening the casing for setting the device for reverse operation.

75 27. A door-checking and closing device normally operative in but one direction comprising in combination door-closing means, checking means co-operative therewith, and means whereby without any disassembly the 80 device may be set for reverse operation.

28. A door closing and checking device combining a casing, a door closing spring and a liquid checking means positioned within the spring, means for selectively rendering said spring effective in opposite directions and means operative upon movement in either direction to center the checking means relative to the spring substantially as described.

90 29. A door closing and checking device comprising a casing, a door closing spring and a liquid checking means positioned within the spring, means operatively to interconnect the spring and checking means and means operative by movement of the door to center the door closing means relative to the checking means.

95 30. A door closing and checking device combining a casing a door closing spring a 100 liquid checking means positioned within the spring.

31. A door check and closer comprising in combination a casing, a spring, a pair of carriers engaging the spring at opposite 105 ends, each carrier being arranged to be held against movement in one direction relative to the casing, a power applying element arranged to engage the carriers alternatively, tension the spring in the same direction upon 110 movement in either direction and reversible fluid checking means to control the return movement of the power applying element when actuated by the spring together with means for relieving friction between certain parts.

115 32. A door-checking and closing device comprising in combination a casing, an arm arranged to be connected to a door, a door-closing spring associated therewith, checking means cooperating with the arm to retard movement thereof in one direction comprising a cylinder within the casing ports in the cylinder and port closure means arranged alternatively to close some ports and open others for reverse operation, a piston within the cylinder and means whereby movements of the piston will set the port closure means for reverse operation.

120 33. A door-closing and checking device 130

comprising in combination a casing door-closing means, checking means cooperating therewith comprising a cylinder, ports in the cylinder, port closing means, a piston 5 mounted for oscillatory movement in the cylinder, the piston being operable to rotate the cylinder relative to the port closing means to set the device for reverse operation.

34. A door-closing and checking device 10 comprising in combination a casing, door-closing means comprising a spring within the casing, and checking means cooperative therewith comprising a hydraulic cylinder and an oscillatory piston therein constructed and arranged to permit relative 15 movement of the cylinder and casing to set the device for reverse operation.

35. A door-closing and checking device comprising in combination door-closing 20 means comprising an arm movable pivotally relative to the casing and checking means cooperative therewith comprising a cylinder having ports and port closure means operable to cause reverse operation of the checking 25 means, the closure means being operable by the said arm to cause reverse operation.

36. A door-closing and checking device comprising in combination door closing means comprising an arm movable pivotally 30 relative to the casing and checking means cooperative therewith comprising a cylinder adjustable to two positions selectively for reverse operation and means whereby the cylinder can be adjusted to either position by 35 movement of said arm.

37. A hydraulic check and closer comprising in combination a door closing means, a checking device cooperating therewith comprising in combination a cylinder, a piston movable therein, a port arranged to open to 40 permit movement in one direction, a port arranged to open to permit free movement during part of the return movement, and to gradually close during further return movement, said port being tapered in area and 45 lying at an angle to the adjacent relatively moving part to distribute friction and wear and a port arranged to open during the latter part of the return movement.

38. A hydraulic check and closer comprising in combination a door closing means, 50 a checking device cooperating therewith comprising in combination a cylinder, a rotatable wing piston therein having a pivoted spindle, a bypass port comprising a groove 55 extending diagonally around the spindle of the wing piston on the side substantially opposite the piston head, said port being tapered at one end to cause a gradual closing thereof. 60

39. A door closing and checking device combining a casing, a door closing spring, a liquid checking means positioned within the spring and means whereby said checking means can be set for reverse operation without opening the casing. 65

In testimony whereof, I have signed my name to this specification this 23rd day of January 1924.

PORTER S. MORGAN.
